UNITED STATES PATENT OFFICE.

BENJAMIN E. LUCKINBILL, OF GUTHRIE CENTER, IOWA.

WATERING-TROUGH.

1,383,646.

Specification of Letters Patent.

Patented July 5, 1921.

Application filed September 18, 1920. Serial No. 411,184.

To all whom it may concern:

Be it known that I, BENJAMIN E. LUCKINBILL, a citizen of the United States, residing at Guthrie Center, in the county of 5 Guthrie, State of Iowa, have invented certain new and useful Improvements in Watering-Troughs; and I do hereby declare the following to be a full, clear, and exact description of the invention, such as will 10 enable others skilled in the art to which it appertains to make and use the same.

This invention relates to animal husbandry, and more especially to feeding devices; and the object of the same is to produce a 15 watering trough made from a single blank of sheet metal folded in such way that it will be exceedingly strong, rests on the lower edges of its sides and ends and cannot be easily overturned, needs but two lines of 20 soldering to make it watertight, and can be readily cleaned of dirt or ice.

These objects are carried out by cutting and folding the blank in the manner hereinafter more fully described and claimed, 25 and as shown in the drawings wherein:

Figure 1 is a perspective view of this trough, set up ready for use.

Fig. 2 is a plan view of the blank from 30 which the trough is made, the dotted lines indicating where folding is to occur.

Fig. 3 is a cross section through the structure and an inner elevation of one end.

Fig. 4 is an end elevation of the structure with the panels folded to shape and the flaps 35 in place, but the wings and lip not yet folded.

The blank designated by the numeral 20 in Fig. 2 is substantially rectangular in outline, and is stamped or cut from a single 40 piece of sheet material—preferably metal—with scores or indentations where it is to be folded as indicated by the dotted lines in this view, and the parts of such blank will be described by the same terms as applied 45 to them after it has been folded into shape. Along one edge of the blank is a side panel 1 and along the other edge the opposite side panel 2, while between these panels are two others 3 and 4 constituting parts of a V-shaped bottom, the four panels being separated 50 from each other by fold lines as indicated at 5. At each end of each side panel is an end wing 6 separated from the panel by a fold line 7. At the ends of 55 the bottom panels are right-angular triangular flaps 8, 18 separated from the panels

by fold lines 9 along their bases, while the upright sides of these two flaps are separated from each other by a slit or cut 10. The hypotenuse 11 of one flap 8 is spaced 60 from the inner edge 12 of the adjacent wings 6, while a triangular lip 13 is connected by a fold line 14 with the hypotenuse of the other flap 18 so that this flap and lip collectively are substantially square. The same 65 structure of parts prevails at the other end of the blank so that if reversed end for end the same description would apply.

In folding this blank into the trough seen in Fig. 1, the bottom panels 3 and 4 are 70 brought up from the intermediate fold line so that they stand at about 90° to each other, and then each side panel is bent down from the outer edge of its bottom panel to an angle of about 45° so that it stands vertical. 75 The flaps 8 and 18 are meanwhile bent up at right angles to their bottom panels so that when the latter are bent into planes at right angles with each other, the flaps will overlie each other, and they may be connected 80 by rivets or otherwise as shown at 15. The end wings 6 are now bent inward at right angles to their side panels and lapped, and they may be connected with each other by rivets 16. The lip 13 is now bent down over 85 the outermost wing, to which it may be connected by rivets 17; or, if preferred, the several overlapping wings and flaps, and the lip may all be connected by a single rivet or by a single set of rivets passing 90 through them. Finally a line of solder is run up the side of the innermost flap 8 along the line 19 where it contacts with the bottom panel 4, and the same at the other end—these being the only 95 lines where leakage might occur. The structure is now complete and its parts are thoroughly braced, leaving no place where an animal could get its snout under the trough and upset it. The lower edges of the side 100 panels and their end wings rest slightly on or may be embedded in the earth, and the trough may be used for feeding or for watering stock. Manifestly it is easy to clean, and even if the water should freeze solid, 105 the lump of ice can be readily dislodged.

What is claimed is:

1. The herein described trough composed of a single piece of sheet material folded to form a V-shaped bottom, vertical sides depending from the edges of the bottom panels, vertical end wings extending from the 110

ends of the side panels and overlapping each other, flaps at the ends of the bottom panels folded at right angles to them and overlapping each other inside said wings, 5 means for connecting the wings and flaps at each end of the structure, and a watertight connection between the free edge of the inner flap and the opposite bottom panel.

2. The herein described trough composed 10 of a single piece of sheet material folded to form a V-shaped bottom, vertical sides depending from the edges of the bottom panels, vertical end wings extending from the ends of the side panels and overlapping each 15 other, flaps at the ends of the bottom panels folded at right angles to them and overlapping each other inside said wings, and a lip on one flap folded outward over the other flap and the lapping wings.

20 3. The herein described trough composed of a single piece of sheet material folded to form a V-shaped bottom, vertical sides depending from the edges of the bottom panels, vertical end wings extending from the 25 ends of the side panels and overlapping each other, flaps at the ends of the bottom panels folded at right angles to them and overlapping each other inside said wings, rivets for connecting said wings and flaps 30 where they overlap, and a lip on the inside flap folded outward over the other flap and the lapping wings.

4. The herein described trough composed

of a single piece of sheet metal folded to 35 form a V-shaped bottom, vertical sides depending from the edges of the bottom panels, vertical end wings extending from the ends of the side panels and overlapping each other, triangular flaps having their bases united by fold lines with the ends of the 40 bottom panels and their adjacent sides separated from each other whereby they may be folded at right angles to the bottom panels and caused to overlap, and fastening means on the innermost flap along its hypotenuse adapted to pass over the hypotenuse of the other flap and the upper edges of both wings.

5. The herein described trough composed 45 of a single piece of sheet material folded to form a V-shaped bottom composed of two panels, sides depending from the edges of the bottom panels, end wings extending inward toward each other from the ends of the side panels, flaps at the ends of the bottom panels folded to overlap each other inside said wings, and a lip on the inside flap folded outward over the other flap and the lapping wings.

In testimony whereof I affix my signature 60 in the presence of two witnesses.

BENJAMIN E. LUCKINBILL.
